UNITED STATES PATENT OFFICE.

CHRIST NELSON AND JAMES ELMER JONES, OF TORONTO, SOUTH DAKOTA.

REVERSING MECHANISM FOR STEAM-ENGINES.

SPECIFICATION forming part of Letters Patent No. 598,433, dated February 1, 1898.

Application filed March 25, 1897. Serial No. 629,192. (No model.)

To all whom it may concern:

Be it known that we, CHRIST NELSON and JAMES ELMER JONES, residents of Toronto, in the county of Deuel and State of South Dakota, have invented certain new and useful Improvements in Reversing Mechanism for Steam-Engines; and we do hereby declare that the following is a full, clear, and exact description of the invention, which will enable others skilled in the art to which it appertains to make and use the same, reference being had to the accompanying drawings, which form a part of this specification.

Our invention relates to means for reversing steam and other similar engines; and its object is to provide an improved construction of the same by which we dispense with the ordinary links now in common use.

The invention consists in the novel construction and combination of parts herein-after fully described and claimed.

In the accompanying drawings, Figure 1 is a plan view of a reversing device constructed in accordance with our invention. Fig. 2 is a section on the line $x-x$, Fig. 1. Fig. 3 is a similar section looking in the opposite direction. Fig. 4 is a longitudinal sectional view.

In the said drawings the reference-numeral 1 designates the driving-shaft of a steam or other engine.

The numeral 2 designates an eccentric formed with an opening through which the driving-shaft passes, and at each side of said opening are circular recesses 3, in which are seated washers or collars 4, fixed to the said shaft by set-screws 5. By this means the shaft can turn or oscillate on the shaft, as herein-after described, but cannot move laterally or lengthwise of the shaft. At one side of said eccentric is a sliding block 6, through which said shaft also passes, and is formed with a groove 7, with which engages a longitudinal rib or feather 8, secured to the shaft to prevent the block from rotating on the shaft. Secured to this block are spiral rods 9, which pass loosely through apertures in the eccentric and their opposite ends secured to a sliding hub 10 on said shaft. This hub is also provided with groove 12 and rib 13, similar to those described above with reference to the sliding block and for the same purpose. This hub is formed with a peripheral groove 14,

with which engages flanges 15 on the inner sides of two semicircular straps 16, formed with lugs 17, through which pass screws 18 for connecting the straps together. Each of these straps is provided with an opposite pin 19, with which engages the forked or bifurcated ends of an angle-lever 20, pivoted to the engine or boiler or other convenient plate and provided with a reversing rod or bar (not shown) for moving the hub laterally on the shaft. The object of this construction is to move the hub and connected block laterally or lengthwise on the driving-shaft to reverse the engine.

The numeral 23 designates an eccentric-strap, and 24 the rod thereof, which operates the cylinder-valve of the engine, which may be of any ordinary or suitable construction.

The operation is as follows: When the block 6 is moved up close to the eccentric, the engine will run in one direction, the friction between the eccentric and the fixed collar being sufficient to cause the eccentric to rotate with the shaft, when the cylinder-valve will be operated, as usual, to alternately admit steam to and exhaust it from opposite ends of the cylinder. To reverse the engine, the hub is moved toward the eccentric by means of the semicircular straps, lever, and reversing-rod, causing the block 6 to be moved away from the eccentric, and by means of the spiral rods passing through the eccentric, which will overcome the friction between the eccentric and washers, the eccentric will be turned on the shaft about one-third of a revolution, which will shift the cylinder-valve and reverse the engine in the manner well known to those skilled in the art.

Having thus fully described our invention, what we claim is—

1. In a reversing mechanism for steam-engines, and other engines, the combination with the driving-shaft, the eccentric thereon, and the fixed washers engaging with said eccentric by frictional contact, of the sliding block, non-rotatable on the said shaft at one side of said eccentric, the spiral rods secured thereto and passing loosely through said eccentric, and the sliding hub to which the other ends of said rods are secured, substantially as described.
2. In a reversing mechanism for steam and

other engines, the combination with the driving-shaft, the eccentric rotatably mounted thereon, and the fixed washers or collars and set-screws engaging with said eccentric by frictional contact, of the sliding block on said shaft having a groove, the rib on the shaft engaging therewith, the spiral rods secured to said block and passing loosely through said eccentric, the sliding hub to which the opposite ends of said rods are secured, the ribs on said shaft engaging with a groove in the hub, the semicylindrical straps, having interior

flanges engaging with a peripheral groove in the hub, the pins on said straps, the bifurcated angle-lever connected therewith and the reversing-rod, substantially as described. 15

In testimony that we claim the foregoing as our own we have hereunto affixed our signatures in presence of two witnesses.

CHRIST NELSON.

JAMES ELMER JONES.
